UNITED STATES PATENT OFFICE

167,463

SHEET SUPPORT FOR AN AUTOMATIC SHEET FEEDING MACHINE OR THE LIKE

Elmer L. Johnson, Chicago, Ill., assignor to Bell
& Howell Company, Chicago, Ill., a corporation
of Illinois

Application June 18, 1949, Serial No. 3,403

Term of patent 14 years

(Cl. D64—11)

To all whom it may concern:

Be it known that I, Elmer L. Johnson, a citizen of the United States, residing at Chicago, State of Illinois, have invented a new, original, and ornamental Design for a Sheet Support for an Automatic Sheet Feeding Machine or the like, of which the following is a specification, reference being had to the accompanying drawing, forming a part hereof.

In the drawing—

Figure 1 is a perspective view of a sheet support for an automatic sheet feeding machine or the like embodying my new design; and

Figure 2 is a perspective view of the design as seen from the back of Figure 1.

I claim:

The ornamental design for a sheet support for an automatic sheet feeding machine or the like, substantially as shown.

ELMER L. JOHNSON.
